Franklin W. Kremer,
by W. M. Finckel, Attorney.

UNITED STATES PATENT OFFICE.

FRANKLIN W. KREMER, OF WADSWORTH, OHIO.

INJECTOR.

SPECIFICATION forming part of Letters Patent No. 299,230, dated May 27, 1884.

Application filed November 19, 1883. (Model.)

To all whom it may concern:

Be it known that I, FRANKLIN W. KREMER, a citizen of the United States, residing at Wadsworth, in the county of Medina and State of Ohio, have invented certain new and useful Improvements in Injectors, of which the following is a full, clear, and exact description.

This invention is in the nature of improvements in the class of injectors represented in my United States Letters Patent No. 282,092, dated July 31, 1883; and the improvements consist in the arrangement and operation of certain valves or cocks for controlling the steam and water, and also in the combination therewith of the overflow, as I shall now proceed to particularly describe and claim.

In the accompanying drawing one form of my invention is illustrated in central longitudinal section, the steam-valves being in elevation, and the machine being in position for starting.

The several sections *a b c* of the injector are preferably connected by ground or ground and packed joints, or rabbeting, as in the patent referred to.

c is the steam-inlet, and *d* the steam-chamber, which latter opens into the suction-chamber *e* through a lifting jet-tube, *f*, in an otherwise solid diaphragm dividing the section *a* into the said steam-chamber and suction-chamber. This jet-tube is opened and closed by a valve, *g*, seating on it, and having a screw-threaded stem, *g'*, running in the gland or bonnet *g''*, and operated by a hand-wheel or handle, *g''*.

h is the combining-tube arranged in the suction-chamber, and having its receiving end centered just below the jet-tube, with a space between them, the said combining-tube being supported by its base *h'*, arranged between or in the joint of the sections *a b*. The section *b* contains the supply-chamber *i*, which is divided by a diaphragm, *i'*, having in it a passage, *i''*. This diaphragm has also a vertical tubular cavity, *j*, meeting a horizontal passage, *j'*, leading outside the section, and this passage has connected with it a cock, *k*, in which the valve *k'* is seated to control the inlet of steam from the pipe *k''*, to convert the injector from a lifting to a non-lifting or forcing machine. The valve *k'* has a suitable screw-threaded stem running in a bonnet, and having an op-

erating wheel or handle, substantially as shown. The pipe *k''* is connected with the cock by a slip-joint, as in the patent referred to. The tubular cavity *j* terminates in the forcing jet-tube *j''*, and I shall hereinafter refer to the cavity *j*, passage *j'*, and tube *j''* as the "forcing-jet." The force-combining tube *l* is arranged by its flange in the joint of the sections *b c*, and its tubular portion centers under the forcing-jet. Holes *l'* in the flange of this combining-tube serve to connect the supply-chamber *i* with the exhaust or overflow chamber *m* in the section *c*, which section connects with the boiler, and has in it the delivery-tube *n*, centered below the force-combining tube *l*. Connected with the section *c* is a cock, *o*, having the valve-seat *p*, an outlet, *p'*, and a bonnet, *p''*. The valve-seat *p* is occupied by a valve, *q*, having a tubular stem, *r*, by which it is connected with the stem *s*. This stem *s* has a nib, *s'*, on which the tubular stem of the valve slips, and a screw-threaded portion, *s''*, by which it is run in and out of the bonnet *p''*, and a hand-wheel or handle, *s''*, by which it is operated. The valve *q* has a movement independent of the stem *s*, is substantially a check-valve, and constitutes the overflow or exhaust controller.

Having thus described the construction and arrangement of my improvements, I will now proceed to set forth the operation. In the drawing the parts are in position for starting, the valve opening the lifting jet-tube *f* for the admission of steam through pipe *c* into the suction-chamber, and the valve-stem being partly withdrawn from the valve *q*, leaving said valve, however, seated on the seat *p*. The cock *k* is closed. Now, the steam escaping through the lifting-jet *f* into the chamber *e* creates a vacuum therein, whereby an inflow of the water through pipe *t* is caused, filling the chamber *e*, and then driven by the steam down through the combining-tube *h*, passage *i''*, and holes *l'* into the overflow-chamber. The pressure coming thence against the valve *q*, it will slip back upon the stem-nib *s'* and open the valve to permit overflow. When the water escapes from the cock *o*, the valve *k'* is opened, letting steam into the supply-chamber *i* through the passage *j'* and jet-tube *j''*, where its pressure acts to drive the water through the combining-tube *l*, whence it es-

capes initially into the exhaust; but the column or jet quickly attains sufficient velocity to force itself through the delivery-tube *n* to the boiler. Now, if the water-supply is not in excess of the steam-pressure, water will also be drawn in between the tubes *l* *n*, and from the receiving or supply chamber *i* through the ports or holes *l'*, and the valve *q* will, by the consequent suction in the exhaust-chamber, be automatically seated. On the other hand, if the valve *q* be positively seated by its stem *s*, and the water-supply be in excess of the steam-pressure, and the steam be inadequate to carry the volume of water to the boiler, a portion of the water will be discharged between the tubes *l* *n* and returned through ports *l'* to the supply-chamber. Thus it will be seen that the ported combining-tube *l* becomes an equalizer and renders the impairment of the jet by varying steam-pressure impossible — a thing not heretofore accomplished, so far as my knowledge extends. With this construction the heretofore commonly employed outside overflow is rendered unnecessary, the ported tube *l* acting as an equalizer, completely obviating the use of one.

On locomotives it is desirable to heat the water in the tanks in cold weather to prevent its freezing, and where the exhaust-valve cannot be closed, as is usually the case, this cannot be accomplished through the medium of the injector; but with my construction of exhaust the heating of this water can be readily done by turning down the stem *s* till the valve *q* is seated, and opening the steam-valve *k'*, when the steam will be blown back and heat the water.

What I claim is—

1. In an injector, the steam-chamber *d*, the valve *g* therein, the suction-chamber *e*, with which the steam - chamber communicates through the lifting jet-tube *f*, under control of the said valve, the combining-tube *h*, aligned with the said lifting jet-tube, the overflow-chamber *m*, the overflow-cock *o* therein, provided with the valve *q*, having automatic play

on its stem, and also by said stem adapted to be positively operated to close said overflow, all combined and arranged to operate substantially as shown and described.

50

2. In an injector, the steam-chamber *d*, the valve *g* therein, the suction-chamber *e*, with which the steam - chamber communicates through the lifting jet-tube *f*, under control of the said valve, the combining-tube *h*, aligned with the said lifting jet-tube, the forcing jet-tube *j*² in the supply-chamber, and communicating with the steam-supply, with an interposed valve, *k'*, the combining-tube *l*, having ports *l'* in its base or flange to open independent communication between the suction and overflow or exhaust chambers, and the overflow-valve *q*, having an automatic and also a positive operation, all combined and arranged to operate substantially as shown and described.

55

3. In an injector, the steam-chamber *d*, the valve *g* therein, the suction-chamber *e*, with which the steam - chamber communicates through the lifting jet-tube *f*, under control of the said valve, the combining-tube *h*, aligned with the said lifting jet-tube, the forcing jet-tube *j*² in the supply-chamber, and communicating with the steam-supply, with an interposed valve, *k'*, the combining-tube *l*, having ports *l'* in its base or flange to open independent communication between the suction and overflow or exhaust chambers, the discharge-tube *n* in the suction or exhaust chamber *m*, aligned with the force-combining tube, and the overflow-valve *q*, having an automatic and also a positive operation, all combined and arranged to operate substantially as shown and described.

60

In testimony whereof I have hereunto set 85 my hand this 15th day of November, A. D. 1883.

FRANKLIN W. KREMER.
